The ornamental design for an electronic article surveillance security gate, as shown and described.

DESCRIPTION

FIG. 1 is a first embodiment of a perspective view of an electronic article surveillance security gate with an opaque antenna mount;

FIG. 2 is a front elevation view;

FIG. 3 is a top plan view;

FIG. 4 is a bottom plan view; and

FIG. 5 is a left side elevation view.

FIG. 6 is a second embodiment of a perspective view of an electronic article surveillance security gate with an at least partially clear antenna mount;

FIG. 7 is a front elevation view;

FIG. 8 is a top plan view;

FIG. 9 is a bottom plan view; and,

FIG. 10 is a left side elevation view.
